UNITED STATES PATENT OFFICE.

JOHN SHELTON, OF DENVER, COLORADO.

DUMP-CAR.

No. 800,410.

Specification of Letters Patent.

Patented Sept. 26, 1905.

Application filed February 13, 1905. Serial No. 245,494.

To all whom it may concern:

Be it known that I, JOHN SHELTON, a citizen of the United States, and a resident of Denver, Colorado, have invented certain new and useful Improvements in Dump-Cars, of which the following is a specification containing a full, clear, and exact description, reference being had to the accompanying drawings, forming a part hereof.

- My invention relates to improvements in dump-cars; and it consists of the novel features herein shown, described, and claimed.

In the drawings, Figure 1 is a side elevation of a dump-car embodying the principles of my invention. Fig. 2 is a top plan view of the car-body shown in Fig. 1, the doors and gearing being omitted. Fig. 3 is a central cross-section. Fig. 4 is a perspective of the body-bolster upon an enlarged scale. Fig. 5 is a cross-section through the body-bolster and door. Fig. 6 is a detail elevation of the gearing. Fig. 7 is a plan view of the dumping-lever latch, the dumping-lever being shown in section. Fig. 8 is a perspective of the latch. Fig. 9 is a perspective of one of the crank-arms. Fig. 10 is a perspective of one of the door-closing arms.

My present dump-car is an improvement or modification of the dump-car shown in my Patent No. 754,351, dated March 8, 1904.

Referring to the drawings in detail, the truss-struts 11 extend downwardly from the truss-blocks 12 and are supported by the truss-rods 13. The outer sills 15 and 16 and the inner sills 17 and 18 rest upon the truss-blocks 12, and the body-bolsters 19 rest upon the sills 15, 16, 17, and 18. The body-bolsters consist of center portions 20, having flat lower faces to rest upon the sills, the arm portions 21 and 22 extending outwardly from the central portions and the attaching-plates 23 and 24 extending outwardly from the arms, the upper faces of the central portions 20 and the arms 22 being A-shaped in cross-section and the whole bolster being cast hollow, as shown in Fig. 5.

The side pieces 25 and 26 rest upon and are attached to the plates 23 and 24. The A-shaped bottom 27 is mounted with its edges resting upon the sills 15 and 16. Hinge-plates 28 and 29 are secured to the upper faces of the sills 15 and 16. The hinge-plates 30 and 31 are connected to the plates 28 and 29, and the doors 32 and 33 are secured to the plates 28 and 29, and the doors 32 and 33 are secured to the plates 30 and 31, said plates 30 and 31 extend-

ing entirely across the doors and beyond the doors to form teeth 34 and 35, said doors swinging upwardly against the arms 21 and 22 and against the lower faces of the sills 25 and 26. The truss-blocks 12 extend beyond the sills 15 and 16 to form stops 36 and 37 to limit the fall of the doors 32 and 33. Shafts 38 and 39 are rotatably mounted through the sills 15 and 17 and 18 and 16, respectively, and arms 40 and 41 extend outwardly from the ends of the shafts at angles of substantially forty-five degrees, there being rollers 42 and 43 upon the outer ends of the arms to engage the doors 30 and 31, so that as the shafts 38 and 39 are rotated the doors are raised to their closed positions. Crank-arms 44 and 45 are fixed upon the inner ends of the shafts 38 and 39, said crank-arms being normally below horizontal positions and extending from the shafts in the same direction as the arms 40 and 41.

A windlass 46 is mounted under the floor 27 above the body-bolsters 19, and chains or cables 47 are attached to the windlass, wound upon the windlass, and extend downwardly and are connected to the links 48, said links connecting the outer ends of the arms 44 and 45, so that when the windlass is rotated the shafts 38 and 39 are operated to close the doors. A gear 49 is fixed upon one end of the windlass 46, and a pawl 50 is mounted in position to engage the gear and hold it against the winding strain. A pinion 51 is mounted upon a trunnion 52 and meshes with the gear 49. A gear 53 is integral with or attached to the pinion 52, and a pinion 54, mounted upon the trunnion 55, meshes with the gear 53. A hand-wheel 56 is attached to the gear 54, so that when the hand-wheel is operated the windlass 46 is operated.

Latching-levers 57 and 58 are pivotally mounted in substantially vertical positions upon the outer faces of the side pieces 25 and 26, there being hooks 59 and 60 upon the lower ends of said levers to engage and latch with the teeth 34 and 35 to hold the doors in their closed positions. The upper ends of the levers 57 and 58 are connected by the bars 61 and 62. A hand-lever 63 is connected at its lower end to the outer face of the side piece 25 by a pivot 64, and said hand-lever is connected to the bar 61 by a pivot 65. A similar hand-lever (not shown) is connected to the outer face of the side piece 26 and to the bar 62, so that when the hand-levers are operated in one direction the doors are released and

when the hand-levers are operated in the other direction the doors are latched in their closed positions.

A housing-plate 66 is attached to the side of the car near the upper end of each of the hand-levers, and a second housing-plate 67 is mounted outside of the plate 66, the ends of the plate 67 being offset to form the opening 68, in which the hand-lever operates. A hinge-plate 69 is secured to the outer face of the plate 67 near its center, said plate being mounted upon a pivot 70, so that the plate will turn edgewise. A second plate 71 is hinged to the plate 69, and a keeper 72 extends from the edge of the plate 71 over the upper edge of the plate 67 and downwardly into the opening 68 to hold the hand-lever 63 to hold the doors latched and closed. When it is desired to release the doors, the keeper 72 is elevated out of engagement with the bar 67 and turned outwardly on its hinge, so as to allow the lever 63 to swing freely in the opening 68.

The car-bottom is open on each side of the center throughout its length, so that the contents of the car may be dumped readily by releasing the hand-levers.

I claim—

1. In a dump-car: supporting-sills; body-bolsters mounted on top of the sills; and doors hinged in position to swing upwardly against the body-bolsters.
2. In a dump-car: transverse truss-blocks; supporting-sills upon the truss-blocks; body-bolsters upon the supporting-sills; side pieces upon the outer ends of the body-bolsters; and doors hinged in position to swing upwardly against the body-bolsters and side pieces.

3. In a dump-car: transverse truss-blocks; supporting-sills upon the truss-blocks; body-bolsters, doors hinged in position to swing upwardly against the body-bolsters; and stops to limit the downward swing of the doors.

4. In a dump-car: supporting-sills; body-bolsters upon the supporting-sills; an A-shaped bottom above the centers of the body-bolsters; doors hinged in position to swing upwardly against the body-bolsters; a windlass; shafts mounted transversely of the sills; cranks upon the inner ends of the shafts and connected to the windlass; and arms upon the outer ends of the shafts to close the doors when the shafts are rotated by the operation of the windlass.

5. In a dump-car: body-bolsters suitably mounted; doors hinged in position to swing upwardly against the body-bolsters; a windlass; means whereby the windlass closes the doors; a hand-wheel; and a train of gearing between the hand-wheel and the windlass.

6. In a dump-car: body-bolsters suitably mounted; doors hinged in position to swing upwardly against the body-bolsters; teeth upon the doors; latches upon the car-body to engage the teeth and hold the doors closed; levers for operating the latches; and means of locking the levers and holding the latches closed.

In testimony whereof I have signed my name to this specification in presence of two subscribing witnesses.

JOHN SHELTON.

Witnesses:

META SCHULZE,
ALFRED A. EICKS.
